ART OF BONDING METAL TO INSULATION

Werner Osenberg, Dresden, Germany

Application December 24, 1937, Serial No. 181,661

8 Claims. (Cl. 219—3)

The present invention is especially concerned with the attachment of metallic bodies to carriers, more particularly in the case of electrical apparatus such as contact assemblies, lamp sockets, sockets for radio tubes or similar apparatus used in radio or the like, and especially where the conducting part is to be fastened to a non-conducting carrier of ceramic material or the like.

For a clearer understanding of the invention it may be noted that where a contact piece of conducting material is to be attached to a carrier of ceramic material which is to be introduced in the usual outlet, the extension of the prong 10 may be introduced through the ceramic carrier and the attachment effected by means of a nut upon the threaded extremity thereof. The requisite pressure in tightening the nut in practice frequently injures the ceramic carrier which as a 15 result of the application of pressure may develop cracks or actually break in two.

If the extension of the contact prong is cemented into a bore in the ceramic carrier a permanently useful connection between the carrier 20 and the prong is not to be depended on because in practice the cement will not hold and the prong may become loose or separate entirely.

Where the extension is to be secured by riveting, that is by the formation of a rivet head, pressure must be exerted in the usual riveting operation of such magnitude, that the ceramic carrier either develops cracks or breaks entirely. Furthermore the heat applied to the rivet in this 30 operation may heat the ceramic material so greatly that as a result of expansion the same will crack or break.

According to the present invention a satisfactory connection is accomplished without strain upon or excessive heating of the ceramic material, 40 by performing the securing operation by the application of heat electrically with the aid of appropriate electrodes.

According to the present invention the ceramic carrier is provided with conformations with 45 which a portion of the surface area of the sheet metal piece is intimately connected by resort to electrodes applied adjacent such conformation to cause the metal to soften at that region and to be snugly engaged with said conformation either by the pressure exerted by the electrodes or by 50 resort to a separate pressure die applied at the heat softened portion. In a specific application the carrier may be provided with a projection of appropriate form, illustratively of a tenon shape and the electrodes of appropriate form

applied to the sheet metal adjacent the sides of the tenon to cause the metal therebetween to become softened and to become readily shaped to the contour of the projection for snug engagement therewith, rendered especially secure by the contraction of the metal in cooling. For localization of the heat generated by the electrodes, the sheet metal might be slotted to form a narrow bridge between the electrodes at which the heat and softening effect are localized. 10 Where the insulating element is in the form of a cylinder and the metal element in the form of a cap to be applied thereto, the cylinder might be provided with peripheral grooves and the electrodes applied to soften the cap metal there- 15 adjacent either to form a bead or a multiplicity of depressions forced into the groove or the rim of the cap might be turned into such grooves.

In the accompanying drawings in which are shown one or more of the various possible embodiments of the several features of the invention,

Fig. 1 is a view in longitudinal cross-section showing the method of attaching thin sheet metal to a ceramic or other insulating surface, 20

 50 Fig. 37 is a side view illustrating another application of the invention,
 Fig. 38 is a view in longitudinal cross-section illustrating the product produced by the arrangement of Fig. 37, and
 55 Fig. 39 is a fragmentary plan view thereof.
 Referring now to Figs. 1 and 2, there is shown a method for securing an angle piece V to a ceramic carrier. The latter may be provided with a tenon-shaped projection V upon which one flank of the angle piece is superposed as shown in Fig. 1. The two electrodes E' and E² with their electric conductors L' and L² are so disposed upon the sheet metal piece that the heating occurs in the length of metal therebetween which is carried on to such extent that the same softens. As a consequence the metal may be drawn about the projection V to form a cap thereover as best shown in Fig. 2. As the metal then cools it contracts to a greater extent than the ceramic carrier which has been heated relatively slightly in the operation, and as a consequence of that contraction the sheet metal cap draws tightly about the ceramic projection to afford an extraordinarily secure and tight seat thereupon.
 75

In this connection it is to be noted that in this process no riveting or the like is required but only the drawing of the material over the projection on the ceramic carrier and the resultant shrinking of the sheet metal part that has been softened in the operation accomplishes the secure attachment.

Referring to Fig. 3, the insulating carrier I is shown with a flat projection tapering slightly to its upper face and the metallic sheet 3 which initially is flat is secured by resort to the electrodes E.

In Fig. 4 an arrangement is shown similar to Figs. 1 and 2 but in this case the flat electrodes E are shaped or formed as tools to press the flat sheet metal about the tenon-shaped projection 2.

In Fig. 5 the electrodes e are in the form of rollers which are particularly useful where the metal part 4 is of considerable width and the tenon-shaped projection 2 of corresponding length.

In Fig. 6 the attachment of the metal strip 5 to a support with an ordinary rather than a tenon-shaped projection 2 is also accomplished with roller-shaped electrodes e with the addition of a pressure roller W, which in combination with the two electrode rollers serves to secure the strip 5 to the carrier I. The pressure roll is especially advantageous where the metal strip is to be securely rolled upon the carrier with the elimination of any open space therebetween. The pressure roll may have a suitable profile according to the cross-sectional form of the projection to which the metal strip is to be attached.

Fig. 7 for instance shows a shape of roller profile for a peak projection and Fig. 8 a similar roller to be used for attaching the metal to a rounded projection.

Where the projection of the carrier I has a circular cross-section, one of the electrodes may be formed in the shape of a ring R as shown in Fig. 9 which in the application effects the positioning of the strip 8 against the projection 2 during softening of the material when the electrode E is applied centrally of the projection to form the assembly shown in Fig. 10.

As shown in Figs. 11, 12 and 13, the application of the metal strip 8 upon a circular projection 2 of the carrier may be effected by the use of two opposed semi-cylindrical electrodes E.

The surface of the ceramic carrier to which the sheet metal is to be applied, may be of any suitable roughened form, for instance with sharp ribs 11 as shown in Figs. 14 and 15, or with rectangular ribs 12 as in Figs. 16 and 17. As shown in Fig. 15 the sharp teeth roughening may be in the form of corrugations extending transversely across all or part of the width of the attachment surface and as illustratively shown in Fig. 17, the roughened areas may be arranged in the form of concentric circular conformations. It is understood that in the use of embodiments such as Figs. 14 to 17 the metal parts may be secured to the carrier by means of pressure stamping dies which have depressions complementary to the projections shown.

In Fig. 18 is shown an embodiment in which the metal part 9 is shown secured to the carrier I at a projection 2 formed by grooves or depressions 13, 14 in the carrier. Such grooves 13 and 14 could also be formed in the interior of a hollow cylinder to be lined with sheet metal.

In order to avoid loss of heat in that part of the metal piece which is to be shaped by the

application of heat, it is desirable, as shown in Figs. 19 and 20 to form slots 16 and 17 which materially minimizes the loss of heat from the bridging part 18 defined thereby. The speed with which this part may be brought to the required plastic condition is materially increased in this manner and metal pieces thus prepared may be more rapidly assembled, with economy of labor and electric power.

As shown in Figs. 21 and 22, the projection to which the metal part 21 is to be attached may be formed as a cylinder. The cylindrical projection 2 for that purpose is provided at its periphery with depressions 19 which extend partially or wholly about the same. To attain rapid heating of the material, at the part to be pressed inward it is desirable to perform the shaping in the manner shown in Fig. 21 where the two electrodes E are disposed in closely contiguous relation in the region of the grooves or depressions but with sufficient space therebetween for the introduction of a pressure die 20 at the softened part, which serves to press the material into the depression 19. As a rule it will not be necessary to press the metal part 21 at its entire periphery into the depression 19, but normally it will suffice if the material is so depressed into two diametrically opposed parts of the depression 19.

In Fig. 23 the depressions 22 are so disposed that the rim of the metal part 23 may be bent thereinto and thereby secure the metal part 23 to the projection 2.

In place of rod-shaped electrodes e, roller electrodes of suitable profile may be utilized, particularly in such cases where the projection 2 is circular in cross-section and has annular depressions 33, 34 as shown for instance in Figs. 24 and 25. In such cases the electrodes e may be passed around the periphery of the metal part 24 or 25 which is also of circular shape. In the embodiments according to Figs. 21 to 25, a normal or a metal glazing or finishing may be introduced. In the case of the temperatures attained in this operation the glazing will melt and pass into intimate engagement between the two parts to be connected so that a gas or fluid-tight closure is attained.

In Fig. 26 is shown a carrier 1 which has two projections 2 to which the metal part 26 is attached with the use of two pairs of electrodes E. Projections 2 are circular in cross-section and correspond with the embodiment shown in Figs. 11 to 13. The electrodes in Fig. 26 are semi-circular in cross-section so that in this manner the attachment of the metal part 26 illustratively shown in the form of a lamp socket may be attained in the same manner as shown in Figs. 11 to 13.

Fig. 27 shows a carrier 1 with a projection 2, circular in cross-section, to which in addition to the metallic part 27 there is simultaneously attached another flat metal part 28. Where illustratively the part 27 represents an electric socket, part 28 may constitute a metallic conductor which leads the electric current to the socket. Both parts 27 and 28 in the embodiment of Fig. 27 are simultaneously attached to the projection 2 by aid of the semi-cylindrical electrodes E.

In order to accelerate the assembly process and thereby save time and power, it is possible, as shown for instance in Fig. 28 to previously form the metallic part 29 roughly to the shape desired, in a purely mechanical manner as shown at 30, which parts are superposed over the projections 2 before the electrodes are applied, in

order to effect accurate and final attachment of the metal part 29 to the carrier 1.

As shown in Figs. 6 and 7, and 21 and 22, the electrodes may be utilized solely for heating and softening the metal parts while special dies or stamps or pressure rolls serve to press the material in place. The shape of the pressure dies or pressure rolls may match that of the projections. This is shown in Figs. 29 to 32. E—E are the two electrodes which effect the application of current to the metal part 31, and 32 is the pressure die or stamp which effects the deformation of the softened metal. The cross-sectional area of the pressure die may be of suitable form as desired. In Figs. 30, 31 and 32 are illustrative examples of such form, Fig. 30 showing a semi-circular contour—Fig. 31 a sharp-toothed serrated contour and Fig. 32 a rectangular-toothed serrated contour.

If it is desired to affix the metal part to a body which has only slight heat conductivity, it is preferable to protect this body or carrier from excessive heating by means of an interlayer as shown in Fig. 33. The carrier 1 here has a projection 2 over which extends the insulating interlayer 35, illustratively made of asbestos and 36 is the metallic piece which is attached to the projection 2 in a single operation with the sheet 35, by use of the electrodes E.

In Figs. 34, 35 and 36 is shown another embodiment for attachment of the metal piece 37 upon the carrier 1 with the cylindrical projection 2. In this case the ceramic part is covered by means of a silver plating 38. The aperture 39 provided in the metal part 37 is desirably of diameter smaller than that of the projection 2. The application of the metal part 37 is preferably effected by aid of two opposed semi-cylindrical electrodes as shown in a number of the previous embodiments including for instance Fig. 13. The portion of the metal part 37 adjacent the aperture 39 is rolled upward in this operation and in the subsequent contraction becomes particularly tightly lodged against the projection 2.

Since a body made of artificial resin or similar materials may be deformed under certain heat applications, that property may be utilized in the application of the metal parts. This is illustrated in Figs. 37, 38 and 39 where the electrodes E are of conical form at their pressure ends. Thereby they press corresponding tangs 40, 41 out of the metal part into the carrier 1. Between the tangs 40, 41 there is thus formed a projection 2.

Having thus described my invention, what I claim as new and desire to secure by Letters Patent is:

1. The method of attaching a flat sheet metal plate to a ceramic carrier which comprises conforming the carrier with one or more surface irregularities, in its otherwise flat face, superposing the plate thereover, applying electrodes to said plate near the boundaries of the area defined by said irregularities, thereby to cause the metal between said electrodes to become softened under heat, and deforming the flat softened metal plate area to press it snugly into engagement with the irregularities.

2. The method of attaching a flat sheet metal member to an insulating carrier with one or more surface irregularities in its otherwise flat face which comprises applying electrodes at portions of the sheet metal member positioned against the carrier and causing the portion of

said sheet metal member between said electrodes to become softened under the heat of the applied current and concurrently with said operation pressing said sheet metal member through said electrodes against said insulating carrier and applying pressure through an auxiliary pressure tool to said sheet metal member throughout the region between the electrodes, thereby to cause the softened sheet metal to be conformed to the carrier.

3. The method of attaching a sheet metal plate to a ceramic carrier provided with a tenon-shaped projection which consists in superposing the metal over the projection, applying electrodes 15 near the opposite edges of the projection thereby to cause the metal between said electrodes to become softened under heat and tucking the thus softened material inward about both sides of the projection by corresponding portions of 20 the electrodes.

4. The method of attaching a sheet metal plate to a ceramic carrier provided with a tenon-shaped projection which consists in superposing the metal over the projection, applying electrodes 25 near the opposite edges of the projection thereby to cause the metal between said electrodes to become softened under heat and tucking the thus softened material inward about both sides of the projection by corresponding portions of 30 the electrodes, while exerting pressure over the entire area of the upper face of the projection by means of a pressure tool interposed between the electrodes.

5. The method of attaching a flat metal plate 35 to an insulating carrier provided with one or more generally circular mounting studs, which

method consists in superposing the metal over the mounting studs, applying semi-cylindrical electrodes to the metal adjacent said studs and causing the disc-shaped portion of the metal bounded by said electrodes to become softened and conformed under pressure snugly to engage and encase the studs on the carrier plates.

6. The method of applying a sheet metal member to a ceramic carrier which consists in glazing the latter with a coating of low melting point, applying electrodes to the sheet metal member to cause the same as well as the glazing to become softened under heat, and shaping the softened metal to the conformation of the carrier, whereby in the subsequent cooling the 15 softened glazing will fill in minute voids between the sheet metal piece and its carrier, to afford a liquid and gas-tight bond therebetween.

7. The method of attaching an electric socket shell to a ceramic carrier provided with one or more unitary cylindrical mounting studs, which consists in applying electrodes into the socket, one pair for each mounting stud, thereby causing the region defined by each pair of electrodes to be softened under the consequent heat and 20 pressing the thus softened material about the 25 stud or studs.

8. An assembly including a ceramic base and a sheet metal piece firmly bonded thereto, said ceramic base comprising a substantially flat face 30 with a tenon-shaped projection integral therewith, the metal element engaging said base and being heat shrunk about the tenon for snug gripping thereof.

WERNER OSENBERG. 35
